UNITED STATES PATENT OFFICE.

LEO F. McNALLY, OF BROOKLYN, NEW YORK, ASSIGNOR TO DAVID W. PYE, OF RED BANK, NEW JERSEY.

TRAP-DOOR FOR GRADE-LEVEL VESTIBULE-CARS.

1,275,714.

Specification of Letters Patent. Patented Aug. 13, 1918.

Application filed June 6, 1917. Serial No. 173,079.

To all whom it may concern:

Be it known that I, LEO F. McNALLY, a citizen of the United States, and a resident of New York, borough of Brooklyn, in the county of Kings and State of New York, have made and invented certain new and useful Improvements in Trap-Doors for Grade-Level Vestibule-Cars, of which the following is a specification.

10 My invention relates to trap doors for grade level vestibule cars, and particularly to the hinge supporting mechanism therefor. In that type of car construction which is referred to above as "grade level vestibule cars," the vestibule door upon either side of the car extends below the trap door. In this construction, in order to open the vestibule door, it is necessary for the trap door to be first raised. The trap door and hinge supporting mechanism therefor must accordingly be of such dimensions that they can occupy the space between the end wall of the car and the vestibule door when the latter is in its open position. On account of the 20 limited space for the trap door and raising mechanism, it has heretofore been the custom to construct the raising mechanism in the form of coil tension springs secured to a prolongation of the hinge mechanism of the door and thus leave the hinge of the trap door unencumbered. It has been found, however, that the torsional type of spring for trap doors contains many advantages 30 over the coil tension spring construction, especially when it is incorporated in and made a part of the hinge mechanism, this construction being now almost universally adopted for elevated platform car construction, wherein the vestibule door is first opened 40 and the trap door then raised against the vestibule door.

It is accordingly an object of my invention to construct a hinge mechanism and associated parts for supporting a trap door for grade level vestibule car construction wherein the raising mechanism comprehends the use of a torsional spring which is incorporated in and made a part of the hinge mechanism.

50 A further object is to provide a hinge mechanism for grade level trap doors which is of strong and compact design and wherein the torsional spring is locked in its adjusted position and so held regardless of the severe

jarring and jolting of the car. My improved design further contemplates the use of new and efficient supporting brackets and associated parts for pivotally securing the trap door to the car. A further object is to construct the various parts of the hinge and raising mechanism so that they may be easily and quickly removed for inspection, replaced if broken by accident, and when assembled and forming a hinge support for the door, capable of rendering long and satisfactory service, so that the trap door will always open in an easy and ready manner regardless of the severe service and varying atmospheric conditions to which it is necessarily exposed.

With these and other objects in view, and with the aim to comply with the various standards of the Master Car Builders' Association concerning car construction, my invention resides in the combination and arrangement of parts and in the details of construction hereinafter described and claimed.

The preferred embodiment of my invention is disclosed in the accompanying drawings, wherein:

Figure 1 is a view in top plan of the trap door in its closed position, and with the accompanying parts of the car represented in horizontal section, also portions of the hinge mechanism being broken away so as to more clearly show the details thereof;

Fig. 2 is a fragmental view in side elevation of the vestibule door of a car, with portions thereof broken away to more clearly depict my improved hinge mechanism upon which the trap door is mounted;

Fig. 3 is a view in vertical section taken on the line 3—3 of Fig. 1, illustrating my improved hinge mechanism for grade level trap door construction;

Fig. 4 is a view in vertical section taken on the line 4—4 of Fig. 3, illustrating the adjusting mechanism for the torsional spring;

Fig. 5 is a view in vertical section taken on the line 5—5 of Fig. 3, showing the details of construction of the pivotal support for one extremity of the trap door;

Fig. 6 is a vertical sectional view taken on the line 6—6 of Fig. 3;

Fig. 7 is a view in vertical section taken on the line 7—7 of Fig. 1; and

Fig. 8 is a view in perspective of the adjusting plug which also serves as a pivotal support for the trap door.

Referring specifically to the several views, 5 a trap door 10 is hingedly secured to the cross-beam 11, while the vestibule door 12 is hingedly secured to the upright post 13; the arrangement and construction being such that as disclosed in Fig. 2, the vestibule door extends below the outer edge of the trap door 10 and is adapted to open thereagainst after the trap door 10 has been raised to its upright position; this particular construction and arrangement of parts 15 being spoken of as of the grade level type, and is used on those cars which do not encounter elevated platforms.

A supporting bracket 14 is secured to the car and is provided with the opening 15 extending therethrough, in which is pivotally mounted a supporting member or plug 16. The supporting member projects beyond the bracket and at one extremity is provided with a groove 17 for the reception 25 of the one end of the torsional spring 18 therein, and is provided at its opposite end with the wrench-engageable head or projection 19. In order that the supporting member will effect a rotatable juncture with 30 the supporting bracket, brass collars 20 are mounted upon the supporting member and provide for the smooth and free adjustment or rotation of the supporting member. The supporting member is provided intermediate 35 its ends with the ratchet teeth 21, which are engaged by a pawl 22, the latter being pivotally secured within an opening 23 in the bracket by the pivot pin 24. The pawl is locked in position and the supporting member 40 accordingly held against rotation by a locking member or screw 25. The trap door 10, as more clearly illustrated in Fig. 7, has secured thereto a cylindrical casing or housing 26, the door itself projecting from the 45 housing or casing in a radial manner. The housing extends over, and is rotatably supported by, the supporting member 16.

The torsional spring 18 is contained within the housing 26, and has the one extremity thereof seated within the groove 17 of the supporting member, and the opposite end 27 seats within a groove 28 contained in a spring seat 29, the latter being in the form of a plug fitting within the housing 26 and secured thereto by the rivets or bolts 30. The spring seat is riveted or secured to the housing at such point as is consistent with the length of the torsional spring 18. Fitting within the extremity of the housing, 55 and rigidly secured thereto, is the pivot bushing 31 which contains the pin-receiving opening 32. A pivot bracket 33 is secured to the car and supports the pivot member 34, the extremity of which extends within 60 the opening 32 in the pivot bushing and

mounts the trap door for hinged movement. In order to lock the pivot member 34 in position, a cotter key or other holding means 35 is fastened to the bracket 33 and extends through the said pivot member.

The housing with which the trap door is provided, extending radially from the trap door, allows the same to swing upward so as to occupy a position directly above the center line of the pivot member and the supporting member 16, and occupying as it does a position radial to the housing and pivot supports, the entire construction occupies a minimum amount of space. In order to properly adjust the spring 18, the pawl locking member 25 is removed and a wrench placed upon the head 19 of the supporting member and the latter forcibly rotated, it being held against reverse rotation by the pawl 22. After the spring has been properly adjusted so as to raise the trap door in a smooth but positive manner, the locking member 25 is again inserted in place and the pawl locked against displacement and the supporting member locked in adjusted position. With the parts as thus constructed and arranged, an efficient and reliable hinge supporting mechanism is provided, and the features and advantages of a torsional spring are incorporated in a grade 95 level trap door construction.

What I claim is:—

1. In a device of the class described, a cylindrical housing; a trap door carried by said housing; a supporting bracket located adjacent one end of said housing; a removable supporting member supported by said supporting bracket and extending therefrom, and adapted to provide a pivotal support for one end of said housing; a pivot bracket located adjacent the other end of said cylindrical housing; a removable pivot carried by said pivot bracket and extending therefrom, and adapted to provide a pivotal support for the other end of said housing; means for securing said removable pivot in place relative to said pivot supporting bracket; and a torsional spring located within said housing, one end of said spring being connected with said supporting member and the other end thereof being operatively connected with said housing.

2. In a device of the class described, a cylindrical housing; a trap door carried by said housing; a supporting bracket located adjacent one end of said housing; a supporting member supported by said supporting bracket and extending into one end of said housing, and having a longitudinally extending groove formed in its periphery and adjacent its inner end; a pivot bracket located adjacent the other end of said cylindrical housing; a pivot carried by said pivot bracket and adapted to provide a pivotal support for the adjacent end of said

- housing; a spring seat located within said housing and secured thereto, and having a longitudinally extending groove formed in its periphery; and a helical torsional spring located within said housing and the ends of which are provided with straight portions adapted to lie within the grooves aforesaid of said spring seat and of said supporting member.
- 10 3. In a device of the class described, a cylindrical housing; a trap door carried by said housing; a supporting bracket located adjacent one end of said housing; a supporting member supported by said supporting bracket and extending therefrom, and adapted to provide a pivotal support for one end of said housing; a series of ratchet teeth upon said supporting member intermediate the ends thereof; a pivotally sup-
- ported pawl carried by said supporting bracket and the free end of which is adapted to engage said teeth; a locking screw adapted to hold the free end of said pawl in engagement with said teeth; means for providing a pivotal support for the other end of said housing; and a torsional spring located within said housing and the ends of which are connected, respectively, with said supporting member and with said housing.
- 15 Signed at New York, borough of Manhattan, in the county of New York and State of New York, this 5th day of June, A. D. 1917.

LEO F. McNALLY.
